W. G. Bradford
ATTORNEY.

UNITED STATES PATENT OFFICE

WILLIAM G. BRADFORD, OF TORRANCE, CALIFORNIA, ASSIGNOR TO J. E. OLIVER, OF FULLERTON, CALIFORNIA

OIL SAVER

Application filed November 24, 1930. Serial No. 497,663.

This invention relates to an oil saver particularly useful in an oil well derrick when a bailer, swab, or the like is being used. The oil which collects on the cable supporting the bailer is stripped off and returned into the tubing thereby preventing it from discharging on the floor of the derrick where it is lost.

An object of my invention is to provide a novel oil saver, the stripper head of which contains all of the releasing mechanism, thereby leaving the tubing entirely open for the tools.

Another object is to provide an oil saver of the character stated, the stripper head of which can be easily and quickly remounted in operative position after it has been carried upwardly by the swab or tools.

Other objects, advantages, and features of invention may appear from the accompanying drawing, the subjoined detailed description, and the appended claims.

In the drawing

Figure 1 is a view half in longitudinal section, and half in elevation.

Figure 2 is a bottom plan view of the stripper head with the releasing ring removed.

Figure 3 is a top plan view of the releasing ring.

Referring more particularly to the drawing, the numeral 1 indicates a pipe section which is suitably mounted on the top of the tubing. A stripper head 2 is releasably mounted on the top of the pipe section 1, as will be further described. The stripper head is provided with a central bore 3 through which the cable supporting the tools extends. A packing block 4 is mounted adjacent the upper end of the head, and this packing block presses against the cable to wipe the oil off of the surface. A nut 5 screws into the top of the head against the block 4 for the purpose of compressing the packing block against the cable.

The stripper head 2 is provided with an integral depending apron 6 which fits around the outside of the pipe section 1. An annular groove 7 is formed adjacent the upper end of the pipe section 1 for the purpose of holding the stripper head in place, as will

be further described. A plurality of latches 8 is pivotally mounted in the stripper head 2, and these latches are each provided with a lip 9 which fits into the annular groove 7 thereby holding the stripper head on the pipe section 1. A coil spring 10 bears against the top of the latches 8 thereby tending to swing the latches into engagement with the groove 7. The latches are all simultaneously swung inwardly and released from the groove 7 by means of a releasing spider 11. The releasing spider is slidably mounted on a plurality of bolts 12 which screw into the stripper head 2. The heads of the bolts are countersunk into the releasing spider, as shown at 13.

A cam lip 14 is provided on the upper outer edge of the releasing spider, the purpose of this lip being to engage each of the latches and swing them outwardly when the said spider is pushed upwardly by a tool moving upwardly in the tubing. It will be evident that as the tool strikes the releasing spider, it will push the same upwardly thus causing the cam lip thereof to engage the latches and swing them into disengagement. The stripper head will then be free and can move up with the tool without in any way injuring the tools or the head.

A packing ring 15 is seated around the outside of the pipe section 1, and the apron 6 bears against this packing so as to seal the space between the head and the pipe section. The apron is preferably formed with a tapered seat 16 which bears against the packing, thus pressing the packing tightly between the apron and the pipe section. A hole 17 may be provided through the pipe section to the inner surface of the packing 15 for the purpose of causing any pressure in the tubing to press the packing tightly against the apron 6. When the stripper head is carried upwardly, all of the releasing and latching mechanism moved with it, and thus the tubing is entirely free and the tools can be inserted therein without difficulty or without striking any intricate mechanism.

Having described my invention, I claim:

1. An oil saver comprising a pipe section, a stripper head mounted on the pipe section,

said pipe section having an annular groove adjacent the upper end thereof, a plurality of latches pivotally mounted in the stripper head, said latches being adapted to engage in the annular groove, a releasing spider, a plurality of bolts extending through the releasing spider and into the stripper head, said spider being slidably mounted on the bolts, said spider being adapted to be engaged by 10 the tools whereby said spider is lifted to release the latches, and springs bearing against said latches whereby the latches are moved into engaged position.

2. An oil saver comprising a pipe section, 15 a stripper head mounted on the pipe section, said pipe section having an annular groove adjacent the upper end thereof, a plurality of latches pivotally mounted in the stripper head, said latches being adapted to engage 20 in the annular groove, a releasing spider, a plurality of bolts extending through the releasing spider and into the stripper head, said spider being slidably mounted on the bolts, said spider being adapted to be engaged by 25 the tools whereby said spider is lifted to release the latches, and springs bearing against said latches whereby the latches are moved into engaged position, an integral apron depending from the stripper head, an annular 30 packing ring between the apron and the pipe section, said apron having a tapered seat engaging the packing whereby the packing is pressed against the pipe section, a cam lip 35 on said spider, said lip engaging the latches to release said latches on upward movement of the spider.

3. An oil saver comprising a pipe section, 40 a stripper head mounted on the pipe section, a plurality of latches pivotally mounted on the stripper head, on the lower end of said head, means on the pipe section engageable by the latches, a releasing spider, means 45 mounting said spider on the stripper head whereby vertical movement of the spider is permitted, spring means bearing against the latches whereby the latches are moved into engaged position, and a cam lip formed on the 50 spider, said lip engaging the latches to swing the same into non-engaging position.

4. An oil saver comprising a pipe section, 55 a stripper head mounted on the pipe section, said pipe section having an annular groove adjacent the upper end thereof, a plurality of latches pivotally mounted in the stripper head, said latches being adapted to engage in the annular groove, a releasing spider, a plurality of bolts extending through the releasing spider and into the stripper head, said spider being slidably mounted on the bolts, said spider being adapted to be engaged by 60 the tools whereby said spider is lifted to release the latches, and springs bearing against said latches whereby the latches are moved into engaged position, a cam lip on said spider, said lip engaging the latches to release said latches on upward movement of the spider.

5. An oil saver comprising a pipe section,

a stripper head mounted on the pipe section, 70 said pipe section having an annular groove adjacent the upper end thereof, a plurality of latches pivotally mounted in the stripper head, said latches being adapted to engage in the annular groove, a releasing spider, a plurality of bolts extending through the releasing spider and into the stripper head, said spider being slidably mounted on the bolts, 75 said spider being adapted to be engaged by the tools whereby said spider is lifted to release the latches, and springs bearing against said latches whereby the latches are moved into engaged position, an integral apron 80 depending from the stripper head, an annular packing ring between the apron and the pipe section, said apron having a tapered seat engaging the packing whereby the packing is pressed against the pipe section, a cam lip 85 on said spider, said lip engaging the latches to release said latches on upward movement of the spider.

In testimony whereof, I affix my signature.

WILLIAM G. BRADFORD.
